UNITED STATES PATENT OFFICE.

FENNER E. WHIPPLE, OF PHILADELPHIA, ASSIGNOR TO THOMAS H. DALLETT
AND GEORGE A. DALLETT, BOTH OF CHEYNEY, PENNSYLVANIA.

AUTOMATIC SWITCH FOR ELECTRIC MOTORS.

SPECIFICATION forming part of Letters Patent No. 450,441, dated April 14, 1891.

Application filed October 13, 1890. Serial No. 367,991. (No model.)

To all whom it may concern:

Be it known that I, FENNER E. WHIPPLE, a citizen of the United States, and a resident of Philadelphia, Pennsylvania, have invented 5 an Improved Automatic Switch for Electric Motors, &c., of which the following is a specification.

My invention relates to that class of switches which are employed in connection 10 with electric motors and are intended to apply the current with gradually-increasing power, the object of my invention being to provide simple and efficient mechanism for operating the switch-plate and for cutting out 15 in succession the resistances which are thrown into the circuit when the switch is first closed. This object I attain in the manner hereinafter set forth, reference being had to the accompanying drawings, in which—

20 Figure 1 is a front view of my improved switch. Fig. 2 is a plan view of the same. Fig. 3 is an end view of part of the device. Figs. 4, 5, and 6 are detached views of parts 25 of the same, Figs. 4 and 6 being on an enlarged scale. Fig. 7 is a sectional view illustrating a special feature of the invention, and Fig. 8 is a diagram illustrating the electrical connections of the switch.

A represents a box or casing, in which are 30 mounted two shafts or spindles B B', the former carrying the sheave or pulley D, and the shaft B' carrying a similar sheave or pulley D', and around these two sheaves passes a belt or band a, having a positive connection 35 with each sheave—as, for instance, by means of a pin a', passing through the belt and through the rim of the sheave. Secured to the belt a is a handle b, which projects through a slot in the casing A, and is guided 40 upon a rod b', mounted within said casing, so that the handle is free to be moved vertically in order to cause movement of the belt in one direction or the other. Secured, in the present instance, to the opposite run of the belt 45 from that which carries the handle b is a block d, and mounted upon the latter is a duplex switch-plate d', which by contact with the two pairs of spring terminal fingers d² at the bottom of the casing A, serves to complete 50 the electrical circuit in the manner here-

inafter set forth. It will be seen that as the handle b is moved upward the switch-plate d' will be caused to descend, so as to close the switch, and when the handle b is depressed the switch-plate d' will be raised and the switch opened.

Each of the sheaves D D' has a counterbalance-weight D², (shown by dotted lines in Fig. 1 and by full lines in Fig. 5,) this counterbalance-weight tending to maintain the switch-plate in either of its extreme positions and preventing accidental movement of said plate. Projecting from the block d is an arm f, and through an opening in the outer end of the latter passes an upright screw-shaft F, rigidly mounted in suitable bearings f' in the casing, the arm f being free to move vertically upon the screw-shaft.

Supported by the arm f is a frame G, which has at top and bottom projecting arms with 70 openings for the passage of the screw-shaft, and projecting from this frame G are contact-arms g, with spring-mounted rollers g', as shown in Fig. 4, for bearing upon the opposite sides of the vertical series of resistance 75 plates or bars h, mounted upon one side of the casing, or there may, if desired, be a simple sliding contact of the arms g with the plates h, the rollers, however, being preferred.

Free to turn in bearings in the frame G is 80 a block H, which has a spring-pin i engaging with the thread of the screw-shaft F, this pin being beveled at the upper corner, (see Fig. 6,) so that while it will yield radially, and thus permit the block H to be raised vertically on 85 the screw-shaft, it will engage with the thread of said screw-shaft on the descent of the block, and thereby cause the latter to rotate, the pin following the thread of the screw. The block H is recessed near the top, so as to form a 90 shoulder m, with which engages a pin m', carried by a slide n, adapted to a bearing in a bracket n', and projecting from this slide n is a pin p, which is engaged by the slotted upper end of a lever J, hung to said bracket 95 n'. The slide n carries a segmental guard-plate s, with a beveled lower edge, and this plate is acted upon by a spring s', tending to project the same and cause the pin m' to engage with the shoulder of the block H. 100

Projecting from the side of the upper sheave D is a pin t, and when the handle b is elevated so as to close the switch the half-turn thereby imparted to the said sheave D causes said pin 5 t to come in contact with the lower arm of the lever J, thereby operating the same, so as to retract the slide n and withdraw the pin m' from engagement with the shoulder m of the block H.

10 As the previous descent of the block d carrying the switch-plate had removed the supporting arm f from beneath the frame G, said frame and its block, on the withdrawal of the pin m', will descend, the speed of this descent 15 being retarded by reason of the fact that the spring-pin i of the block H is compelled to traverse the thread of the screw shaft F.

The frame G is connected by a system of links w to a block w' at one side of the casting, the system of links being such as to freely permit the vertical movement of the frame G, and serving to convey the current from the said frame G to the block w' as the frame moves vertically.

20 25 The electrical connections are, as described hereinafter, such that when the switch is first closed the current passes through the entire series of resistances; but as the frame G descends the resistance-plates h are successively 30 cut out of the circuit until the rollers or contacts g finally make contact with the lowest plate of the series and are received within spring-guides g², carried by said lower plate, so as to insure a good electrical connection at 35 this point.

In opening the switch downward movement of the handle b, and a consequent upward movement of the block d, effects the lifting of the frame G and its block H, the beveled 40 top of the latter, as it approaches the limit of its upward movement, pushing back the catch m' until the latter engages with the shoulder m.

45 Projecting from the block H is a pin x, and if the circumferential position of the block H is such that on rising to its full extent the spring-pin i would rest upon the highest point of the thread on the screw-shaft F, and hence would not descend, the contact of the beveled 50 lower end of the guard-plate s with said pin x will cause such circumferential movement of the block as will bring said pin i into position to engage the thread. As the block H descends upon the screw-shaft F, there is a 55 natural tendency to accelerated movement, and this may be corrected by a gradual diminution of the pitch of the thread of said screw, the pitch being greatest at the top and least at the bottom, as shown in Figs. 1 and 3. 60 Such graduation of the pitch of the screw might be considered an objection, however. Hence in many cases I prefer to employ in place of the same a form of centrifugal friction-brake. For instance, in Fig. 7 I have 65 shown a pair of levers K hung to the block H, the depending arms of these levers being thickened or weighted and their upper arms

acting upon friction-shoes k, which bear upon the threads of the shaft F, the latter in this case having a uniform pitch. As the block H 70 rotates during its descent, the weighted levers are thrown outward by centrifugal force, and the shoes k are therefore pressed upon the screw-shaft so as to act as friction-shoes and thus retard the descent of the block. The 75 levers may act directly, if desired, however, and a single lever may be used instead of two; or more than two levers may be employed where circumstances warrant such use.

80 Various electrical connections may be devised without affecting the proper operation of the switch. In the drawings, however, the binding-posts 1 and 2 represent the terminals of the line-wires. A post 3 is intended to be connected to the field and armature of the 85 motor, a post 4 to the field only, and a post 5 to the armature only. The switch-plate d' has, as before stated, two portions 6 and 7, and the terminal d² has four fingers 8, 9, 10, and 11. In this case there should be an electrical connection between the post 2 and the finger 9, a fusible strip 12 being by preference 90 interposed in this connection.

Both the block w' and the finger 8 are intended to be connected to the post 4, while 95 the post 1 is connected to the finger 10, the post 3 to the finger 11, and the post 5 to the lowest plate of the resistance series.

The connecting-wires are not shown in Fig. 1, as they would only tend to confuse the representation of the mechanical parts of the switch, to which my invention especially relates; but the electrical connections are shown in the diagram Fig. 8.

100 When it is not convenient to mount the switch in the vertical position shown, the parts may be otherwise arranged, a spring in such case taking the place of gravity as a means of causing the movement of the slide G, when it is released on closing the switch.

110 Having thus described my invention, I claim and desire to secure by Letters Patent—

1. The combination, in an electrical switch, of a pair of sheaves, a belt passing around the same, and a switch-closing plate carried by 115 said belt, substantially as specified.

2. The combination, in an electrical switch, of a pair of sheaves and a belt passing around the same and provided with a switch-closing plate and with an operating-handle, substantially 120 as specified.

3. The combination, in an electrical switch, of a pair of sheaves, a belt passing around the same, a switch-closing plate and operating-handle connected to said belt, and guide-rods for said switch-closing plate and operating-handle, substantially as specified.

4. The combination, in an electrical switch, of a belt or band carrying the switch-closing plate with a pair of sheaves carrying said 125 belt or band, and having counterbalance-weights tending to retain the switch-plate in its extreme positions, substantially as specified.

5. The combination, in an electrical switch, of a series of resistances, a screw-shaft, and a slide traversing said resistances and having a rotatable block engaging with said screw-shaft, substantially as specified.

6. The combination, in an electrical switch, of a series of resistances, a screw-shaft, a slide traversing said resistances and having a rotatable block engaging with said screw-shaft, and a switch having an arm for acting on said slide, substantially as specified.

7. The combination, in an electrical switch, of a series of resistances, a screw-shaft, and a slide adapted to traverse said series of resistances and having a rotatable block with spring-pin for engaging with the thread of said screw-shaft, substantially as specified.

8. The combination, in an electrical switch, of a series of resistances, a screw-shaft, a slide adapted to traverse the series of resistances and having a rotatable block engaging with said screw-shaft, a removable support or retainer for the slide, and means for withdrawing said retainer upon the closing of the switch, substantially as specified.

9. The combination, in an electrical switch, of a pair of sheaves, a belt or band carrying the switch-plate, a series of resistances, a screw-shaft, a slide adapted to traverse the series of resistances and having a rotatable block engaging with said screw-shaft, a removable retainer for said slide, a lever acting on said retainer, and a pin or projection on one of the sheaves for operating the lever on the closing of the switch, substantially as specified.

10. The combination, in an electrical switch,

of a series of resistances, a screw-shaft, a slide adapted to traverse the resistances and having a rotatable block engaging with the screw-shaft, and means, substantially as described, for retarding the movement of the block on said shaft, substantially as specified.

11. The combination, in an electrical switch, of a series of resistances, a screw-shaft, a slide adapted to traverse said series of resistances and carrying a rotatable block engaging with said screw-shaft, and a centrifugal governor carried by said block and serving as a friction-brake to retard the movement of the same on the screw-shaft, substantially as specified.

12. The combination, in an electrical switch, of a series of resistances, a screw-shaft, a slide adapted to traverse said series of resistances and having a rotatable block engaging with said screw-shaft, a pin projecting from said block, and a beveled guard-plate for acting on said pin, substantially as specified.

13. The combination, in an electrical switch, of a series of resistances, a screw-shaft, a slide adapted to traverse said series of resistances and having a rotatable block engaging with said screw-shaft, and a series of links whereby current can be conveyed from the slide to a fixed block during the movement of the slide, substantially as specified.

In testimony whereof I have signed my name to this specification in the presence of two subscribing witnesses.

FENNER E. WHIPPLE.
